United States Patent Office

Des. 214,710
Patented July 15, 1969

214,710

BOOT JACK

Russell F. Killoran, 31 River Road, Grandview, N.Y.

Filed May 13, 1968, Ser. No. 11,889

Term of patent 14 years

Int. Cl. D2—99; D31

U.S. Cl. D86—10

FIG. 1 is a top plan view of a boot jack showing my new design.

FIG. 2 is a bottom plan view thereof.

FIG. 3 is a side elevational view, looking from the right side of FIG. 1 thereof.

FIG. 4 is a side elevational view, looking from the left side of FIG. 1 thereof.

FIG. 5 is a front elevational view thereof.

FIG. 6 is a rear elevational view thereof.

FIG. 7 is a top plan view of a second embodiment of my design wherein the design of FIG. 1 has been adapted for a two jaw boot jack.

FIG. 8 is a side elevational view, looking from the left side of FIG. 7 thereof.

FIG. 9 is a front elevational view thereof.

FIG. 10 is a bottom plan view thereof.

FIG. 11 is a side elevational view, looking from the right side of FIG. 7.

FIG. 12 is a rear elevational view thereof.

I claim:

The ornamental design for a boot jack, substantially as shown and described.
